(57) **CLAIM**

The ornamental design for a caulk nozzle cap, as shown.

DESCRIPTION

FIG. 1 is a perspective view of a caulk nozzle cap showing my new design viewed from the front;

FIG. 2 is a perspective view thereof viewed from the back; FIG. 3 is a side view thereof, the opposite side being a mirror image;

FIG. 4 is a rear-end view thereof; and, FIG. 5 is a front-end view thereof.

The phantom showing of the ribs form no part of the claimed design.
